FILTER

Reginald Herbert Chaffey, Guildford, England,
assignor to Vokes Limited, Guildford, England

Application February 2, 1948, Serial No. 5,763
In Great Britain May 30, 1947

4 Claims. (Cl. 183—49)

1

In the manufacture of filters in which a filtering medium such as felt or suitable textile material (hereinafter included when felt is referred to) is supported on a stiffer medium, there have been various arrangements for making a joint at the edges. For instance, in a deeply pleated or star-shaped element in which felt is carried by wire gauze, the marginal portions of the felt have been turned over the edges of the gauze and secured by a row of stitching run through the two layers of felt and the intermediate layer of gauze. For many purposes this is satisfactory, but where the filter has to withstand a considerable difference of pressure, the ordinary wire gauze is somewhat inclined to deform. In such circumstances, also, such stitching may be undesirable because the holes made by the passage of the needle in stitching to wire gauze the type of felt used to give fine filtration with considerable back pressure are not always negligible.

The present invention is designed to provide an effective edge joint applicable where the felt is supported on wire gauze but more especially intended to enable perforated metal to be effectively used as the supporting medium.

The main idea underlying the invention is the use of stitching at or outside the edge of the supporting medium to produce a roll or bead or pipe of the filtering medium at the bend where it is turned over the edge of the supporting medium.

Typical forms of the invention are illustrated by the accompanying drawings in which:

Figure 1 shows in elevation, partly sectioned, a filter unit adapted for filtration of fluid passing from inside to outside.

Figure 2 is an underside plan of the same,

Figure 3 is a fragmentary detail to much enlarged scale, and

Figure 4 is a view similar to Fig. 3 of a modified form.

The unit shown in Figs. 1 and 2 is of well-known type in which a star-shaped filtering element 1 (Fig. 2) is clamped between end caps 2 and 3 by means of a nut 4 engaging a screw 5 carried by a spider 6. The fluid to be filtered enters at inlet 7 and in case of excessive resistance to its passage due to clogging of the filtering element, the element moves downwardly, away from its operative position against the upward pressure of a spring and the fluid is bypassed through the ports 8.

The star-shaped element 1 is formed from a support 11 of perforated sheet material with the felt 12 turned over both its edges with a line of stitching 13 running along about an eighth of an inch or less from the bend in the felt, so that the edge of the perforated sheet 11 lies against a row of stitching 13 between the main part of the felt and the turnover 12a, which may conveniently

2

extend about half an inch. A length of the combined material can then be crimped or pleated in known fashion and bent round and joined to make a "star-shaped" element as shown or used as a panel, as in the case of the ordinary stitched-on felt and wire gauze.

The piping at the edges, when compressed, makes an excellent joint of fairly substantial width (see Fig. 3) and the compression ensures that the needle holes are not exposed as when the felt is stitched to a wire gauze.

A similar arrangement can be used as shown at Fig. 4 with wire gauze 14, the cut ends 15 of the wire of the gauze being preferably turned in to make an edge that will lie snugly against the piping.

In either case a suitable binding or edging 16 of suitable material such as soft metal or rubber or plastic material may be applied to the edges 20 of the supporting medium before the felt is bent over them if desired. The piping can also be filled with or an internal dressing of latex or other suitable material used at the bend if desired in particular cases. Normally, however, 25 the joint in its simple form should be satisfactory.

It will be noted that the invention, from one aspect, provides a filtering screen in which perforated metal supports the filtering medium and a piping of the filtering medium is arranged to 30 form joints at the edges.

I claim:

1. A filter element comprising a stiff foraminous sheet support and a sheet of filter medium on one side of said support, the opposite edges of 35 said filter sheet being folded over and stitched adjacent the folds to define channels removably surrounding the coinciding edges of said support.

2. A filter element as defined in claim 1 wherein in said support comprises a perforated sheet.

3. A filter element as defined in claim 1 wherein in said support comprises a wire gauze.

4. A filter element as defined in claim 1 wherein in an edging strip is applied around the edges of said support to protect said channels from abrasion.

REGINALD HERBERT CHAFFEY.
